(57) **CLAIM**

The ornamental design for a transitional race track section for toy vehicles, as shown and described.

DESCRIPTION

FIG. 1 is a front isometric view of a transitional race track section for toy vehicles in accordance with the new design;

FIG. 2 is a top plan view thereof;

FIG. 3 is a side elevational view thereof, the opposite side being a mirror image thereof.

FIG. 4 is a bottom plan view thereof;

FIG. 5 is an elevational view of one end thereof; and,

FIG. 6 is an elevational view of the opposite end thereof.

The broken lines in FIGS. 1, 2 and 4 are intended to show environmental structure and form no part of the claimed design.
